UNITED STATES PATENT OFFICE.

BARENT J. BOICOURT, OF COLORADO SPRINGS, COLORADO, ASSIGNOR, BY MESNE ASSIGNMENTS, TO C. & C. ELECTRIC & MANUFACTURING COMPANY, A CORPORATION OF NEW JERSEY.

METHOD OF AND APPARATUS FOR PREVENTING SPARKING IN DYNAMO-ELECTRIC MACHINES.

1,121,065.

Specification of Letters Patent.

Patented Dec. 15, 1914.

Application filed January 27, 1911. Serial No. 605,003.

To all whom it may concern:

Be it known that I, BARENT J. BOICOURT, a citizen of the United States, residing at Colorado Springs, Colorado, have invented 5 certain new and useful Improvements in Methods of and Apparatus for Preventing Sparking in Dynamo-Electric Machines, of which the following is a clear, full, and exact description.

10 The present invention relates to an improvement in dynamo electric machines in the broad sense, that is, either a dynamo for generating current or a motor for utilizing current, and has for its object more 15 particularly the prevention of excessive sparking in such machines under all conditions of operation.

The purposes and general theory of the ordinary interpole motor are well understood as for instance in the patents to 20 Mather #321,990 dated July 14, 1885 and Pfatischer #775,310 dated Nov. 22, 1904, and need not be more particularly described herein. It is sufficient to mention that 25 interpoles are employed for the purpose of providing an interpole magnetic field for the armature coils undergoing commutation to assist in reversing the currents in said coils. The electro-motive force generated 30 in the armature coils tending to maintain the current in one direction and resist the change in direction thereof I prefer to call the reactance voltage, and the electro-motive force generated in opposition thereto by 35 the interpole field I prefer to call counter-reactance voltage. It is desirable for sparkless commutation that this counter-reactance voltage at all times equal in value the reactance voltage or even slightly exceed 40 the same so as to more readily cause a reversal of the current in the armature coils undergoing commutation. The reactance voltage of course depends and varies directly with the armature current and the 45

commutating coils of the interpoles are usually connected in series with the armature in an attempt to vary the magnetism of the interpoles in accordance with the load on the armature and thus generate a counter-reactance voltage equal to or superior to the reactance voltage at all times. It has been found however, that these ideal conditions 50 do not occur, although for small variations

of armature current the arrangement is fairly satisfactory; but that even with the 55 commutating coils connected in series with the armature, the interpole field and consequently the counter-reactance voltage induced thereby does not vary in strength proportionately to the reactance voltage induced by the armature current, and during 60 heavy overloads bad sparking will occur. This is partly due to the tendency of the interpoles to become magnetically saturated by increased current in the commutating 65 coils and partly due to the effect on the interpole field of the increased main field distortion caused by increased armature reaction. Consequently good commutation is not obtained with these former interpole ma- 70 chines when the armature current is increased beyond certain limits due to the failure of the interpole field to respond in strength proportionately to the armature current. In the present embodiment of my invention I 75 have shown one means for remedying these defects of former interpole motors. In the form shown I generate a magneto-motive force for the interpole field which varies in one ratio with the armature current for normal loads and which is suddenly jumped up to vary with said armature current in a higher ratio during abnormal loads. If the means for thus accelerating the magneto- 80 motive force of the interpole field are prop- 85 erly adjusted for the currents to be commutated and are also arranged to act instantaneously with the change of armature current, good commutation can be obtained 90 under all practical conditions.

In the drawings which show the preferred manner in which my invention may be carried out, Figure 1 is a diagrammatic illustration of a direct current shunt-wound motor arranged with my improvement 95 thereon; and Fig. 2 is a diagram of characteristic curves.

Referring first to Fig. 1, 2 indicates the armature motor rotating in the direction of the arrow; 3 and 10 indicate the main field 100 poles for the armature which it is observed are shunt-wound from the main motor circuit 22 and 23. 4 and 4' represent the pole pieces for the interpoles and are wound as shown with main commutating coils 1 and 105 8 respectively, connected in series with the

armature to provide a definite number of 5 interpole turns for the armature current. The usual armature contact brushes are shown at 15 and 15'. It will be observed that the interpoles are also wound with auxiliary commutating coils 6 and 9 normally disconnected from any line and therefore not energized but which may when occasion arises provide additional interpole turns for said armature current. An 10 adjustable resistance 7 may also be included in the local deenergized circuit of these auxiliary commutating coils to properly adjust their action as may be desired.

15 The present invention contemplates the use as shown of main commutating coils connected in series with the main motor circuit for normal operation of the motor under ordinary loads and the inclusion of the 20 auxiliary commutating coils in the main motor-circuit during overloads to vary the magnetism of the interpoles as required. In the drawings I have shown diagrammatically merely a preferred form of construction and arrangement of connections for accomplishing these desired results. The 25 main motor circuit 22, 23 is provided with a break formed by separated contacts 12, 12, adapted to be bridged by block 11 which 30 may be operated by suitable electro-magnetic means indicated by a solenoid 5 and relay circuit controlling switch 14. The auxiliary commutating coils 6 and 9 are preferably included in a local circuit normally open by 35 separated contacts 13. These connections are thus arranged to show in a simplified way how the motor may be operated for normal loads with only the main commutating coils in series with the armature, and 40 how a sudden overload may be imposed upon the armature and simultaneously the auxiliary commutating coils be added in series to the armature so that the interpole field may be strengthened to take care of 45 the increased reactance voltage.

When the block 11 bridges the contacts 12, the motor may be considered as operating under normal load. The main commutating coils 1 and 8 are properly proportioned to 50 take care of this normal load and slight variations thereof for sparkless commutation. If it is desired to impose an overload on the armature, the switch 14 can be opened to allow block 11 to drop away from contacts 12 and bridge contacts 13. This will 55 immediately connect the armature in series with the main and auxiliary commutating coils, all in a locally closed circuit, which practically short-circuits the armature. As 60 is well known, short-circuiting the armature generates a great overload of armature current and produces what is known as a dynamic brake for quickly stopping the motor. In the use of these interpole motors for operating 65 machinery such as planers, it is the

common practice to short-circuit the armature for applying a dynamic brake in this way and cause a quick reversal in rotation. The auxiliary commutating coils 6, 9 are properly proportioned to take care of this sudden and unusual overload on the armature for sparkless commutation. With the ordinary interpole machine, however, the tremendous overload thus imposed upon the armature caused very injurious sparking. Consequently one application of my invention may be to avoid sparking under these conditions of use.

Referring more particularly to Fig. 2, illustrating certain characteristic curves of my interpole motor, line E—S is a measure of amperage and line E—O a measure of voltage. The diagonal line E—T is then characteristic of the reactance voltage of the armature coils undergoing commutation. The line E—K may be regarded as the characteristic curve of the counter-reactance voltage for any definite number of coils on the interpoles. The lines E—T and E—K are drawn in this way to illustrate their changing value relative to one another through different armature loads or amperage. Of course the ideal condition would be to have the line E—K coincide with line E—T, or perhaps gradually diverge therefrom in an upward direction; in other words, to have the counter-reactance voltage equal but opposite to the reactance voltage at all times with a perhaps slight surplus as before stated. It is observed that line E—K on small loads remains fairly close to line E—T but on larger loads rapidly departs therefrom. The dotted lines A—B and C—D indicate the limits of departure for line E—K relative to line E—T before injurious sparking begins. Assuming E—Z to be the normal load imposed on the armature, the reactance voltage and the counter-reactance voltage is Z—N. The main commutating coils 1 and 8 are so proportioned as to cause line E—K to intersect line E—T at N at normal load so that the widest latitude is given in either direction for the armature current to vary before sparking begins. If the armature current is increased beyond E—X, the intersection I of E—K with C—D shows that sparking will begin unless something is done to prevent it. This prevention is accomplished by changing the character of line E—K to E—G—H. This is brought about as before stated, by means of the auxiliary commutating coils 6 and 9 on the interpoles. The intersection G of E—G—H should be directly above intersection I of E—I—K so that the reactance voltage W—X will be opposed as well by G—X counter-reactance voltage as by I—X counter-reactance voltage, thus allowing a gradual as well as an abrupt increase of the reactance voltage to be

taken care of for sparkless commutation by the sudden jump of counter-reactance voltage. The additional commutating coils 6 and 9 are properly proportioned to effect this result.

It is obvious that various changes and adaptations of my invention as here illustrated may be made without departing from the spirit and scope of the invention as expressed in the appended claims.

What I claim as new is—

1. The combination with a dynamo electric machine having an armature, main commutating coils and normally deenergized auxiliary commutating coils, of means for connecting the main commutating coils in the main motor circuit for normal operation, and for disconnecting said main coils and then connecting the armature, the main and the auxiliary commutating coils in a local closed circuit for braking.

2. In a direct current dynamo electric machine in combination, an armature, main field poles therefor, interpoles, main commutating coils on said interpoles arranged to be energized during the operation of the machine, auxiliary commutating coils on said interpoles, and means for energizing and deenergizing said auxiliary commutating coils for varying the magnetism of said interpoles as required.

3. In a direct current dynamo electric machine in combination, an armature, main field poles therefor, interpoles, main commutating coils on said interpoles arranged to be connected in series with said armature during the operation of the machine, auxiliary commutating coils on said interpoles, and means for energizing and deenergizing said auxiliary commutating coils for varying the magnetism of said interpoles in greater degree than the changes caused by a variation of armature current flowing in said main commutating coils.

4. In a direct current dynamo electric machine in combination, an armature, main field poles therefor, interpoles, main commutating coils on said interpoles arranged to be connected in series with said armature during the operation of the machine, auxiliary commutating coils on said interpoles, and means for connecting and disconnecting said auxiliary commutating coils with and from said armature, for varying the magnetism of said interpoles in greater degree than the changes caused by a variation of armature current flowing in said main commutating coils.

5. In a direct current dynamo electric machine in combination, an armature, main field poles therefor, interpoles, main commutating coils on said interpoles arranged to be connected in series with said armature during the operation of the machine, auxiliary commutating coils on said interpoles,

and electromagnetically-operated means for connecting and disconnecting said auxiliary commutating coils with and from said armature, for varying the magnetism of said interpoles in greater degree than the changes caused by a variation of armature current flowing in said main commutating coils.

6. In a direct current dynamo electric machine in combination, an armature, main field poles therefor, interpoles, main commutating coils on said interpoles arranged to be connected in series with said armature during the operation of the machine, auxiliary commutating coils on said interpoles, and means for connecting said auxiliary commutating coils in series with said armature and disconnecting the same therefrom for varying the magnetism of said interpoles in greater degree than the changes caused by a variation of armature current flowing in said main commutating coils.

7. In a direct current dynamo electric machine in combination, an armature, main field poles therefor, interpoles, main and auxiliary commutating coils on said interpoles, said main commutating coils arranged to be connected in series with said armature during normal operation of said motor, and electro-magnetically operated means for connecting said armature, main and auxiliary commutating coils in a locally closed circuit for braking.

8. The method of operating an interpole electric machine through various loads without excessive sparking, which consists in generating a magneto-motive force for the interpole field, which varies with the armature current of said machine in one ratio for normal loads on said armature, and at a time no later than the occurrence of an overload upon said armature, jumping said magneto-motive force suddenly to an increased ratio with respect to said armature current.

9. The method of operating an interpole electric machine through various loads without excessive sparking, which consists in generating a magneto-motive force for the interpole field, which varies with the armature current of said machine in one ratio for normal loads on said armature, and at a time no later than the occurrence of an overload upon said armature, jumping said magneto-motive force suddenly to an increased ratio with respect to said armature current and at a time no later than the cessation of overload upon said armature, jumping said magneto-motive force back to its normal ratio with respect to said armature current.

10. The method of operating an interpole electric machine through various loads without excessive sparking, which consists in generating a magneto-motive force for the interpole field, which varies with the

- armature current of said machine in one ratio for normal loads on said armature, imposing an overload upon said armature and at a time no later than the occurrence of said overload jumping said magneto-motive force suddenly to an increased ratio with respect to said armature current.
11. The method of operating an inter-pole electric machine through various loads without excessive sparking, which consists in generating a magneto-motive force for the inter-pole field, which varies with the armature current of said machine in one ratio for normal loads on said armature, imposing an overload upon said armature and at a time no later than the occurrence of said overload jumping said magneto-motive force suddenly to an increased ratio with respect to said armature current, removing the overload from said armature and at a time no later than the removal of said overload jumping said magneto-motive force back to its normal ratio with respect to said armature.
12. The method of operating an inter-pole electric machine through various loads without excessive sparking, which consists

in conducting the armature current through a definite number of turns about said inter-pole to generate a magneto-motive force for said inter-pole field, and at a time no later than the occurrence of an overload upon said armature conducting said armature current through an additional number of turns about said inter-pole.

13. The method of operating an inter-pole electric machine through various loads without excessive sparking, which consists in conducting the armature current through a definite number of turns about said inter-pole to generate a magneto-motive force for said inter-pole field, imposing an overload upon said armature and at a time no later than the occurrence of said overload conducting said armature current through an additional number of turns about said inter-pole.

Signed at Colorado Springs this 2nd day of May 1910.

BARENT J. BOICOURT.
